VARIABLE MESSAGE HIGHWAY SIGN

Robert A. Nelson, 567 Deal Parkway,
West Allenhurst, N.J. 07711

Filed May 13, 1974, Ser. No. 469,629

Term of patent 14 years

Int. Cl. D20—03

U.S. Cl. D96—12 R

FIG. 1 is an oblique view of a variable message highway sign of my new design with the louvres in the closed position.

FIG. 2 is an elevation view of the sign of the present invention with louvres in the closed position.

FIG. 3 is a plan view of the sign of my new design.

FIG. 4 is a side view of the sign of my new design.

FIG. 5 is a rear view of the sign of my new design.

FIG. 6 is an oblique view of the variable message highway sign of my new design with the louvres in the open position.

I claim:

The ornamental design for a variable message highway sign, as shown and described.
